UNITED STATES PATENT OFFICE.

WILLIAM R. BENNETT, OF ELMWOOD, CONNECTICUT.

STEEL-HEATING FURNACE.

1,244,578.

Specification of Letters Patent. Patented Oct. 30, 1917.

Application filed August 16, 1917. Serial No. 186,498.

To all whom it may concern:

Be it known that I, WILLIAM R. BENNETT, a citizen of the United States, residing at Elmwood, in the county of Hartford and State of Connecticut, have invented certain new and useful Improvements in Steel-Heating Furnaces, of which the following is a specification.

This invention relates to a steel-heating furnace, being used for heating steel pieces of various kinds, in the hardening and tempering thereof. The furnace for illustration, is particularly intended for the hardening or treatment of high-speed or tungsten steel. The primary motive I have in view is the provision of an article of the character set forth by which the preliminary or initial, secondary or intermediate and final or drawing heats can be accomplished in a ready and quick manner. The compartments in which these operations consecutively occur are superimposed and preferably are interiorly cylindrical which is a desirable structure to insure the maximum effects in any one given chamber. As a matter of fact I prefer that the furnace be of cylindrical construction, although this may not always be necessary.

In the drawings accompanying and forming part of the present specification I have shown one of the several convenient forms of embodiment of the invention which I will set forth fully in the following description. I am not restricted to this showing; I may depart therefrom in several respects within the scope of the invention defined by the claims following said description.

Referring to said drawings:

Figure 1 is a vertical sectional view of a furnace involving the invention.

Figs. 2 and 3 are horizontal sections on the lines 2—2 and 3—3 respectively of Fig. 1, looking in the direction of the arrows.

Fig. 4 is a detail of the upper portion of the furnace as seen from the front.

Like characters refer to like parts throughout the several views.

The furnace is denoted by 2 and as shown it is cylindrical, which as I have already noted is the desirable but not essential construction. Said furnace has three chambers or compartments as 3, 4 and 5 which as shown are superposed and coaxial. Said chambers or compartments 3, 4 and 5 are preferably cylindrical, and I might observe at this point that it is more desirable that

the compartments be of this shape than the exterior of the furnace, although the latter has its advantages. The furnace 2 as shown is mounted on a suitable foundation or support as 6. Beneath the lowermost chamber 3 is disposed a heating chamber or combustion compartment as 7, the heat from which may be derived in any convenient manner, preferably from a single or unitary heater as the oil burner 8 (or several of them if necessary), directed into the heating or fire chamber 7, as will hereinafter more particularly appear.

Describing the furnace selected for illustration more in detail, it comprises the base member 9 resting on the foundation or equivalent support 6 and which as shown is of cylindrical fire-brick or similar composition. This cylindrical member or enlarged disk 9 sustains the circular brick 10 which in turn supports the member or disk 11 constituting a suitable floor for the chamber 3 and also of fire-brick, the space between the two parts 9 and 11 and inclosed by the ring or band 10 presenting the fire or heating chamber 7 to which I have already referred.

The fire-brick portion of the furnace which has thus far been partly described, is incased by a shell as 12 preferably of metal and which consists usually of superimposed rings. Said shell or housing 12 extends from the support 6 to the top of the furnace. The lowermost band of the shell or housing 12 has a perforation 13 registering or coinciding with a perforation or opening in the band or ring 10, to receive the tip or nozzle portion of the burner 8. In practice this burner will be provided with suitable regulating means as common. The disk 11 is surmounted by the band or ring 15, a counterpart of the ring 10 except as to depth. The band 15 of fire-brick or the like, is very much higher or deeper than the ring 10. It rests on the disk 11 and is surmounted by the disk 16, the several elements 11, 15, and 16 presenting jointly the chamber 3 to which I have already alluded, and all of them as will be understood being of fire-brick or something of a similar nature.

Although I have described the parts 11 and 16 as being of disk construction, I do not necessarily mean to imply that they are circular. It is not imperative in fact that they be circular, although their main portions each denoted by 17 are preferably so, as will be seen best on inspection of Fig.

3. This disk 16 presents a suitable floor for the compartment 4. The main portions or bodies 17 of these parts 11 and 16 are circular and are provided with diametrically 5 opposite tongues or projections 18 and 19 which rest in or on the wall portion of the furnace body. The main portions 17 it will be observed are separated or spaced from the inner surfaces of the compartments or 10 chambers 3 and 4 as at 20, in view of which circumstances the lower compartment 3 is in communication by way of openings with the heating or fire chamber 7 and the chamber 3 in turn is likewise in communication 15 with the chamber 4, so that the heat can rise to effect the proper action upon the contents of the two chambers. The tongue portions of the parts 11 and 16, as will be understood, are flush with the outer surface of 20 the body of the furnace.

The tongue portions 18 and 19 of the dividing piece 16 are surmounted by a ring or band 21, which is practically a counterpart of the band or ring 15, although a trifle shallower. This band 21 in turn is 25 surmounted by the circular element or disk 22, the periphery of which is in the plane of the outer surface of the fire-brick or analogous body of the furnace. This disk 22 30 constitutes the roof or top of the second or middle chamber 4. The chambers 3 and 4 have openings 23 and 24 respectively for the introduction of the necessary stock or articles thereinto.

35 Although these openings 23 and 24 which as will be understood correspond with similar openings in the shell or jacket 12 may be covered in any desirable way, I prefer to employ in connection with each of them two 40 doors denoted respectively by 25 and 26, and 27 and 28, the doors 25 and 26 coöperating and a like statement applying to the doors 27 and 28. These doors are externally tapered, and they can be in each case separately or simultaneously opened, depending 45 upon the character of the stock to be introduced into the compartments 3 and 4. If a small piece or pieces of stock are to be introduced into either or both of the compartments, the lower door can be opened, whereas if larger pieces, both doors can be opened.

The doors are preferably hinged as at 29 to the metal shell 12, and their marginal portions when the doors are closed fit against 55 the shell to thoroughly shut the openings. The bodies of the doors may be of metal and may be hinged as already described, while the parts of the doors which fit within the openings 23 and 24 may be of fire-brick 60 or equivalent substance. To facilitate the draft in the initial or primary chamber 3 and the consequent heating of the steel prior to hardening and tempering, the said chamber may have extended therefrom near the 65 upper side, the opening 30 which draws the

heat upward and thus accomplishes the desired object. All of the chambers except as herein noted are imperforate and flueless, features of importance.

The arrows in Fig. 1 illustrate in part 70 the path of the heat waves, the heat passing through the two lateral openings 20 from the fire chamber 7 into the primary chamber 3 and from thence by way of similar openings 20 into the chamber 4. Fitted closely 75 within the upper portion of the shell or jacket 12 and separated by a space as 31 from the disk 22 is the practically circular metal plate 32 which constitutes the bottom of the upper chamber 5, the wall of said upper chamber being the ring or band 33 of fire-brick or the like, which obviously is surrounded by the metallic shell 12, the upper edges of the two parts being flush. This 80 annular member or ring 33 and upper portion of the metal shell 12 are surmounted by the crown piece 34 which may be also of metal and which has a downturned flange 35 inclosing comparatively closely the top portion of the shell or jacket 12. Said annular member or ring 33 has an opening 36 which is a counterpart of the openings 23 and 24 already described and which is controlled by doors 37 and 38, practically duplicates of the doors already set forth.

The space 31 under the uppermost chamber 5 has means such as the openings or perforations 39, for the admission of atmospheric air, there being any desirable number of these openings 39 which are formed 100 at suitable intervals in the shell or jacket 12. They are controlled in the present case by damper means as the circular strip 40 which generally has an up and down movement on the said shell 12 to cover more or less or entirely the series of openings 39 to thereby regulate the temperature in the topmost compartment or chamber 5.

This damper or circular strip 40 may be 110 operated in any desirable manner preferably by a thermostat such as that denoted in a general way by 41. Said thermostat involves in its organization a hollow body 42 surmounting the crown or top plate 34 practically centrally thereof and inclosing the 115 two thermostatic bars 43, duplicates of each other and secured at their bases or butts to the outer or upper surface of the crown plate 34. The two thermostatic elements 43 practically cross and to their free ends are connected bands 44 and 45 which traverse guide rollers each denoted by 46, mounted upon the crown plate 34. The band 44 as shown is connected to the rear end of the damper 40, while the band 45 is connected to the cross piece or bar 47 which in turn has bands 48 connected to and depending therefrom and united to the damper 40 near the front end thereof as shown best in Fig. 4. In connection with the upper chamber 5 is also 120

130

a thermometer 49, the elongated base portion 50 of which extends through the roof or crown plate 34.

The compartment or chamber 4 first receives the steel pieces to be hardened and tempered, and there is developed therein a suitable temperature which ordinarily does not exceed 1600 degrees Fahrenheit. After the steel pieces have been in this chamber or compartment 4 the requisite length of time, they are taken from thence and introduced into compartment 3 where they are subjected to a temperature in the neighborhood or 2250 degrees F. They are left in this intermediate chamber the desired length of time and are taken from thence, quenched and afterward put into the topmost compartment 5 in which the temper is drawn.

What I claim is:

1. A furnace for treating steel pieces, comprising three superposed heating chambers, a combustion compartment positioned immediately below the lowest chamber, passages disposed uniformly in or near the periphery of the floors of the two lowest chambers, to provide communication for the products of combustion through the two lowest

chambers, the uppermost chamber being out of communication with the products of combustion and being heated by the heat of the 30 chamber below.

2. A furnace for treating steel pieces, comprising three superposed heating chambers, a combustion compartment positioned immediately below the lowest chamber, 35 passages disposed uniformly in or near the periphery of the floors of the lowermost chambers, to provide communication for the products of combustion through the two lowest chambers, said uppermost chamber being out of communication with the products of combustion being heated by the heat of the 40 chamber below, the furnace having an air space below the floor of the uppermost chamber and said chamber having means for the admission of air at given intervals to reduce or hold at a given degree the temperature of the uppermost chamber. 45

In testimony whereof I affix my signature in the presence of two witnesses.

WILLIAM R. BENNETT.
